CONTROL MECHANISM FOR PRESSES

Elbert L. Hyde, Shaker Heights, Ohio, assignor
to The American Laundry Machinery Company,
Norwood, Cincinnati, Ohio, a corporation of
Ohio

Application September 3, 1937, Serial No. 162,293

4 Claims. (Cl. 192—131)

This invention relates to improvements in pressing machine control mechanism.

An object of the invention is to provide a novel control mechanism for a power closed pressing machine in which the control means for the power means is operated by two spaced safety manuals. These manuals have two stages of operation, a first stage for energizing the power means but during which, upon release of one or both manuals, the press opens; and a second stage of operation for setting a stay-put valve for holding the power means energized, after which the manuals may be released and the press will remain closed. The second stage of manual operation is prevented until the press is safely closed.

The novel features of my invention will be more clearly understood from the accompanying drawing and description and the essential features will be summarized in the claims.

In the drawing, Fig. 1 shows an end elevation of a pressing machine in open position with my novel control mechanism shown diagrammatically; Fig. 2 is a similar view showing the pressing machine in safe closed position and showing the control mechanism in a corresponding position; Fig. 3 is a diagrammatic view of the control mechanism of Figs. 1 and 2, showing the position of the parts after second stage operation of the manuals; while Fig. 4 is a diagrammatic view of the control mechanism after the press is fully closed and the manuals are released.

In Fig. 1 I have shown a pressing machine having a frame 10 carrying a bed 11 and a yoke 12 adapted by oscillation to move a pressing head 13 into and out of engagement with the bed 11 in response to movement of toggles 14 by a fluid motor 15. A valve 16 is provided with a casing 17 and a core 18. The casing 17 has ports 17a, 17b and 17c. The core 18 has a Y-shaped passage 18a. The core has a rigid operating arm 18b which is connected by a yieldable link 19 with a whiffletree 20. The opposite ends of the whiffletree are connected by links 21 with manuals 22 and 23 respectively. These manuals are normally held in unactuated position by springs 24. Blocks 25 limit the manuals to a first stage of movement until the press is safely closed. These blocks are rigid with shaft 26 which has an arm 27 connected by rod 28 to a portion of the press mechanism. In the present instance this rod passes through a slotted bracket 29 on toggle 14. The rod has collars 28a and 28b and is normally biased to hold the blocks in the position of Fig. 1 by a spring 30. Valve 31 has a casing 32 and a core 33. The

casing has ports 32a, 32b, 32c and 32d. The core has a passageway 33a and is provided with a rigid arm 33b which has a slotted connection with one arm of bellcrank 34 which is pivotally mounted at 34a on a suitable part of the frame. A pin 20a on the whiffletree is adapted to engage the other arm of bellcrank 34 during the press operation. Motive fluid is supplied at conduit 35 which leads to port 32c and through conduit 36 is in communication with port 17b. Conduits 37 and 38 connect motor 15 with ports 17a. Conduits 37 and 39 connect motor 15 with port 32d. Conduit 40 connects ports 17c and 32a.

In operation, with the pressing machine in the open position of Fig. 1, the operator depresses manuals 22 and 23 until they engage blocks 25. Operation of both manuals is necessary to move core 18 from the position of Fig. 1 to that of Fig. 2. During this movement the yieldable link 19 is not compressed. When valve 16 is thus moved to the position of Fig. 2, fluid is supplied to motor 15 through conduits 35 and 36, core passage 18a and conduits 38 and 37. This will close the press, but upon release of either manual springs 24 will return the manuals, moving the whiffletree 20 so that core 18 is moved partially or entirely back to the position of Fig. 1 and sufficiently to disestablish the supply through valve 16, whereupon the press of course would open. When the press reaches safe closed position, blocks 25 are moved to the position of Fig. 3 by the straightening toggles acting through rod 28. This permits second stage movement of the manuals to the position of Fig. 3, during which time the core 18 of valve 16 remains in the same position as in Fig. 2 because of stop 41, which causes a compression of the yieldable link 19. This additional movement of the manuals, however, causes sufficient movement of whiffletree 20 to cause the arm 20a thereof to engage bellcrank 34, moving it in a clockwise direction about its pivot and moving the core 33 of valve 31 to the position of Fig. 3. It will be noted that in the position of Figs. 1 and 2 the passageway 33a of this core 33 serves as a portion of the exhaust passage from motor 15. However, when moved to the position of Fig. 3, the core 33 cuts off the exhaust conduit 40 and establishes a by-pass supply for motor 15 independently of valve 16. This by-pass supply is through conduit 35, port 32c, core passage 33a, port 32d and conduits 39 and 37. Since valve 31 is of the stay-put type and will remain in any position in which it is placed, the manuals may now be released as shown in Fig. 4, whereupon these manuals in valve 16 return to the

position of Fig. 1 while the press remains closed. It will be noted in Fig. 4 that while valve 16 is in position to connect motor 15 with exhaust conduit 40, as in Fig. 1, this exhaust conduit is now closed because of the changed position of the valve core 33. The press thus remains closed until the operator moves arm 34b of the bellcrank 34 in a clockwise direction, returning valve 31 to the position of Fig. 1, thus exhausting motor 15 and permitting the press to open.

What I claim is:

1. In a pressing machine having coacting relatively movable pressing members and power actuated operating mechanism therefor, a primary power supply control member for said mechanism, spaced safety manual means for actuating said control member, said manual means having two stages of operation, a first stage for actuating said pressing members to closed position and a second stage comprising a movement other than said first stage movement for causing a maintaining of said members in closed position, there being an operative connection between said control member and said manual means in the first stage of operation arranged to require coincidental use of both hands of an operator to effectively actuate said control member to power supply position, said control member being normally urged to power cut-off position when said manual means is released, means preventing second stage movement of said manual means until said pressing members reach safe-closed position, a secondary power supply control member for said mechanism independent of said primary control member, said secondary control member being arranged for movement to power supply position by second stage movement of said manual means, and said secondary control member being movable to fluid cut-off position to cause opening of the press.

2. In a pressing machine having coacting relatively movable pressing members and power actuated operating mechanism therefor, a primary power supply control member for said mechanism, spaced safety manual means for actuating said control member, said manual means having two stages of operation, a first stage for actuating said pressing members to closed position and a second stage comprising a movement other than said first stage movement for causing a maintaining of said members in closed position, there being an operative connection between said control member and said manual means in the first stage of operation arranged to require coincidental use of both hands of an operator to effectively actuate said control member to power supply position, said control member being normally urged to power cut-off position when said

manual means is released, means preventing second stage movement of said manual means until said pressing members reach safe-closed position, a secondary power supply control member for said mechanism independent of said primary control member, said secondary control member being adapted to stay put in a position in which it is placed, said secondary control member being arranged for movement to power supply position by second stage movement of said manual means, and said secondary control member being movable to fluid cut-off position to cause opening of the press.

3. In a pressing machine having coacting relatively movable pressing members and fluid actuated operating mechanism therefor, primary and secondary fluid supplies for said mechanism, each including a valve in series in the supply system having a normally closed fluid inlet passage and a normally open fluid outlet passage, said primary supply valve being normally urged toward fluid cut off position, said secondary supply valve being adapted to stay put in any position, a conduit connecting the outlet passages of both valves in series, spaced safety manual means for actuating said control members, said manual means having two stages of operation, first and second stages respectively for actuating said primary and secondary supply valves to open the inlet passages and to close the outlet passages thereof, said second stage comprising a movement other than said first stage movement, means preventing second stage operation of said manual means until said pressing members reach safe-closed position, and said secondary supply valve being movable to fluid cut-off position to cause opening of the press.

4. In a pressing machine having coacting relatively movable pressing members and fluid actuated operating mechanism therefor, primary and secondary fluid supplies for said mechanism, control means for said primary fluid supply normally urged to fluid cut-off position, control means for said secondary fluid supply, two-hand safety manual means for actuating said control means, said manual means having two stages of operation, first and second stages respectively for actuating said primary and secondary supply control means to fluid supply position, said second stage comprising a movement other than said first stage movement, means preventing second stage movement of said manual means until said pressing members reach safe-closed position, and said secondary supply control means being movable to fluid cut-off position to cause opening of the press.

ELBERT L. HYDE.
